PURIFICATION OF HYDROCARBON OILS

James A. Reid and Walter A. Schulze, Bartlesville, Okla., assignors to Phillips Petroleum Company, Bartlesville, Okla., a corporation of Delaware

Application June 17, 1935, Serial No. 27,109

5 Claims. (Cl. 196—30)

This invention relates to improvements in processes for sweetening petroleum distillates by means of copper halides.

More specifically it relates to the conduct of processes for sweetening mercaptan-bearing petroleum oil with a solution of a copper salt and a soluble chloride in a readily controllable manner, yielding under all circumstances a doctor sweet and otherwise satisfactory product of good 10 stability as to color and other characteristics.

The sweetening of gasolines with copper halides has been described in the prior art. The process involves the conversion of mercaptans in the oil to disulfides with simultaneous conversion 15 of the copper from the cupric to the cuprous state, the cuprous copper being regenerated to the cupric condition by aeration. In practicing the process, and especially when sweetening gasolines containing unsaturated compounds, it has often been difficult or impossible to produce a 20 product with sufficient color and gum stability; the instability is apparently the result of certain undesirable side reactions.

Since we have discovered that this difficulty 25 may be overcome by controlling the reactivity of the copper solution during the operation of the process, a particular object of our invention is a means for measuring the reactivity of such copper treating solutions.

We have found that the sweetening power or 30 reactivity of a copper halide sweetening solution can be determined by measuring a relative oxidation potential of such a solution. When the concentration and other characteristics of the 35 treating solution are so controlled that this oxidation potential, as determined in a manner to be described, is kept within certain limits, very superior products result from the sweetening of certain gasolines, and especially cracked gasolines.

40 Specifically, by oxidation potential here is meant the potential developed between a polished platinum or gold electrode and a saturated calomel half cell when the two are contacted with the copper solution.

The several factors which affect this oxidation 45 potential are: concentration of the copper solution, both in total copper and in total halide; temperature of the solution; relative amounts of copper in the cuprous states; and also the presence of other salts and substances. The effect of temperature on oxidation potential is illustrated in Figure 1. It will be noted that the oxidation potential of a solution containing 45 50 grams cupric copper and 98 grams chloride per

liter at 76° F. is equal to that of a solution only $\frac{2}{3}$ the concentration, but at 105° F. In Figure 2 is shown the rate of increase in the oxidation potential with increasing concentration of pure cupric chloride in the solution. In addition, the effect of increase in oxidation potential as a result of increase in chloride concentration is illustrated. Figure 3 illustrates the effect of small amounts of cuprous copper on the oxidation potentials of two copper solutions.

The examples in Table I illustrate the interrelation of some of these factors and indicate various ways in which a constant oxidation potential may be maintained.

Example	Copper conc. grams/liter	Chlo. conc. grams/liter	Cuprous-cupric ratio	Temp. deg. F.	Oxidation poten. millivolts
1	45	98	0.00050	66	380
2	45	98	0.00100	94	380
3	34	74	0.00030	93	380
4	48	53	0.00015	95	380

Examples 1 and 2 represent solutions containing the same amounts of copper and chloride; the cuprous copper concentration has been allowed to increase so as to exactly counterbalance the change in oxidation potential which would normally result from increase in temperature. In Example 3 the copper and chloride concentrations are $\frac{3}{4}$ those of the first two examples, the temperature is approximately the same as in the second example. In order that the oxidation potential remains constant, the cuprous copper concentration was diminished. Example 4 illustrates the fact that the copper to chloride ratio may be altered and the effect compensated by varying the cuprous-cupric ratio. It is evident from the foregoing that the oxidation potential of the treating solution may be varied and controlled by either one or more of these factors.

In the sweetening of gasoline by means of copper halide solutions, unsatisfactory results may be obtained as a result of the treating solution possessing too high as well as too low oxidation potentials. Copper chloride solutions of low oxidation potential are unsatisfactory for sweetening gasoline, in that cuprous mercaptides are left in the oil and produce what has heretofore been referred to as a "delayed doctor test". Therefore, a completely sweet product does not result when the oxidation potential of the treating solution is below the values given herein. Many gasolines contacted with copper chloride solution

of high oxidation potential are entirely "sweet" to the "doctor test", but possess undesirable properties, such as inferior color, and color and gum instability. It has been found, however, that an 5 entirely satisfactory product may be obtained through suitable control of the sweetening solution strength throughout its cycle of sweetening and regenerating. By means of the factors already discussed the oxidation potential of the 10 regenerated solution may be maintained below a maximum value; through limitation of the extent of spending, as by limiting the volume of gasoline per volume of treating solution, the 15 solution strength may be kept above a minimum value.

In practice it has been found that the minimum 20 value of the oxidation potential for satisfactory operation at average atmospheric temperature is 330 to 350 millivolts. While this is not an absolute 25 lower limit of possible operation, nevertheless operation at somewhat lower potentials necessitates further control and precaution not necessary above this limit. The maximum value of 30 oxidation potential for satisfactory operation is completely dependent on the stock being treated. A gasoline containing only stable saturated hydrocarbons may be treated with a copper solution of 500-600 millivolts strength with very satisfactory results. But in treating relatively unstable, 35 readily oxidized cracked gasolines, for example from West Texas crudes, solution strengths in excess of 430-450 millivolts are undesirable in that excessive color and gum instability result. In the treating of these less stable gasolines the 40 limits of desirable values of oxidation potential are most narrow, and thus a controlled solution method is of greatest value; such controlled solution is, however, necessary for optimum treatment of any stock.

45 Examples of the sweetening of sour West Texas cracked gasoline under satisfactory and unsatisfactory conditions are given. The charge stock was the same, containing approximately 0.02 per cent mercaptan sulfur. The gasoline after contacting with an equal volume of copper solution was separated from the copper solution and stabilized by means of a sodium sulfide wash; the colors of the resultant gasoline after treatment and at the end of a month's storage are given 50 in the table.

	High oxidation potential	Satisfactory operation	Low oxidation potential
55 Temperature.....	100° F.	100° F.	100° F.
Oxidation potential of			
(a) Initial solution.....	451	401	368
(b) Final solution.....	430	376	337
Doctor.....			
Initial color (Saybolt).....	Sweet	Sweet	Trace sour
Color after treating.....	25	25	25
60 Color after 30 days' storage in	21	25	25
glass.....	12	23	16

The difference between initial and final oxidation potentials is due to the increase in cuprous 65 content of the copper solution as a result of the cupric copper reduced to cuprous copper during the conversion of mercaptans to disulfides. This difference in oxidation potentials of the solution

before and after the sweetening step is dependent upon the amount of cuprous copper formed per unit volume; this in turn depends upon the sourness (mercaptan content) of the gasoline and the ratio of copper solution to gasoline. Our improved process permits close control of the treating solution so that satisfactory operation is constantly secured. In the series of tests from which the above results are quoted, excellent operation 10 was obtained in the range 415-360 millivolts. 15

The oxidation potential as here described may be used for the control of any copper sweetening solution, though ordinarily solutions containing appreciable copper ions and chloride and/or bromide ions will be those found most useful. 15 Such solutions may be used to treat or "sweeten" any oils containing mercaptans, such oils being generally of the nature of kerosene, gasoline and other light petroleum distillates. Usually the 20 solutions will contain halide ions in excess of the quantity necessary for the formation of the corresponding cupric salt.

Our process of sweetening and means of control is not to be limited by any example given by way of illustration, but to include all that 25 come within the scope of the following claims, wherein it is to be understood that the term oxidation potential is intended to include only the potential as obtained in a manner equivalent to that herein described. 30

We claim:

1. A process of sweetening mercaptan-bearing petroleum oil comprising contacting the oil with a metallic halide solution having an oxidation potential within the range of 330 to 450 millivolts. 35

2. A process of sweetening mercaptan-bearing petroleum oil comprising contacting the oil with a treating solution consisting of a copper salt and a soluble chloride, said treating solution having an oxidation potential within the range of 330 to 40. 450 millivolts.

3. A process of sweetening mercaptan-bearing petroleum oil comprising contacting the oil with a treating solution consisting of a copper salt and a soluble chloride, said treating solution having an oxidation potential within the range of 330 to 45. 450 millivolts, separating the oil from the treating solution, contacting the oil with a stabilizing solution consisting of an alkaline sulfide, and separating the finished oil from the sulfide solution. 50

4. In the process of sweetening petroleum distillates by contacting them with oxidizing solutions of copper halides, the improvement which 55 consists in maintaining the oxidation potential of the copper salt solution, while in contact with the said distillate, within the limits of 330 to 450 millivolts.

5. In the process of sweetening petroleum distillates by contacting them with oxidizing solutions of copper halides, the improvement which 60 consists in maintaining the oxidation potential of the copper salt solution, while in contact with the said distillates, within the limits of 360 to 415 millivolts. 65
